Attorneys

UNITED STATES PATENT OFFICE.

GEORGE A. MEISNER, OF OAK PARK, ILLINOIS.

FOUNTAIN BRUSH.

Application filed September 6, 1923. Serial No. 661,287.

To all whom it may concern:

Be it known that I, GEORGE A. MEISNER, a citizen of the United States, residing at Oak Park, in the county of Cook and State 5 of Illinois, have invented certain new and useful Improvements in Fountain Brushes; and I do declare the following to be a full, clear, and exact description of the invention, such as will enable others skilled in the 10 art to which it appertains to make and use the same.

This invention relates to an improved fountain brush for use in cleaning automobile bodies and the like, and one object of 15 the invention is to provide a brush which may be connected with a hose so that water may be applied to the body of the automobile and dirt removed from the same without the finish being injured by becoming 20 scratched.

Another object of the invention is to so construct this device that the nozzle portion thereof may include a hose-engaging nozzle and an outer cleaner-carrying nozzle 25 which is adjustably carried by the hose-engaging nozzle and will be provided with a valve seat co-operating with a valve head upon the hose-engaging nozzle so that through adjustment of the cleaner-carrying 30 nozzle, the flow of water may be readily controlled.

Another object of the invention is to provide improved means for releasably connecting the cleaner head with the cleaner-carrying nozzle so that this cleaner head 35 may be easily and quickly removed or put in place and securely held in the proper position when in place.

This invention is illustrated in the accompanying drawing, wherein:

Figure 1 is a view showing the improved hose attachment with the nozzles in longitudinal section and the cleaner head in elevation.

Figure 2 is a view showing the nozzles in side elevation.

Figures 3, 4 and 5 are sectional views taken along the lines 3—3, 4—4 and 5—5 respectively of Fig. 1.

This improved cleaning device has been provided with a hose-engaging nozzle indicated in general by the numeral 1 and a cleaner-carrying nozzle indicated in general by the numeral 2. These nozzles are adjustably connected so that the flow of water

from the hose-engaging nozzle may be controlled by proper adjustment of the cleaner-carrying nozzle and further may be entirely removed one from the other so that the nozzles may be thoroughly cleaned when necessary.

The hose-engaging nozzle 1 has been provided with a socket portion 3 which is internally threaded as shown at 4 in Fig. 1 and is provided along its outer face with the longitudinally extending ribs 5 so that this socket portion can be firmly gripped by the hand or by means of a suitable wrench and this socket screwed firmly upon the usual coupling provided with a hose. The shank 6 extends forwardly from the socket 3 and is externally threaded as shown so that the cleaner-carrying nozzle 2 and a lock nut 7 may be screwed upon the shank portion of this nozzle 1. The forward end 75 portion of this shank 6 terminates in a head 8 which forms a valve head and is tapered to provide an annular face through which extend the openings or ports 9. The water will pass through these openings 9 when the device is in use.

The cleaner-carrying nozzle 2 is provided with an elongated shank portion 10 which has its forward end portion closed but provided with a plurality of water outlet ports 85 or openings 11 so that the water may be sprayed upon the cleaning brush carried by this nozzle. A socket portion 12 is provided for this nozzle 2 and internally threaded so that this socket portion 12 may 90 be screwed upon the shank portion 6 of the socket 1. At the junction of the shank 10 and socket 12, there has been provided an internal annular shoulder 13 which tapers towards the shank 10 and provides a valve 95 seat for engagement by the tapered valve head 8 of the nozzle 1. From an inspection of Fig. 1, it will be readily seen that by turning the nozzle 2 upon the shank of the nozzle 1, the valve seat may be moved into and out of closing engagement with the valve head. After the nozzle 2 has been adjusted upon the nozzle 1 to the proper point, the lock nut 7 may be screwed into tight engagement with the rear end of the socket 12 and the nozzle 2 will be securely but releasably locked in the desired position.

The cleaner head will be provided with strands formed of yarn or other soft material in the preferred form. It will be under-

stood however that the cleaner head may have the strands formed of any material desired so that the brush may be used for cleaning surfaces which require a soft material to prevent scratching or may be used for other purposes, where a brush having stiffer strands would be desirable. If desired, the device may be provided with several cleaner heads having strands formed of 10 different materials and the desired cleaner head will be put in place according to the work to be performed. These strands 14 will be secured between the twists of the wires 15 and will extend radially from these 15 wires. The end portions of certain of the strands will extend in close contact with the end portion of the nozzle 2 when the brush head is in place and therefore the brush head may be thoroughly saturated with the 20 water. The end portions of the wires extend beyond the bristles or strands 14 and provide twisted stem portions 16 which are passed through perforated ears 17 carried by the nozzle 2. These stems 16 extend 25 longitudinally along the socket 12 and are engaged by a clamp 18 which fits about the socket 12 and has been provided with offset portions forming pockets 19 to receive the stems 16. This clamp 18 is provided with 30 the usual tightening bolt 20 so that the clamp may be drawn tightly into a clamping position. It will thus be seen that the brush head may be securely held in place but may be removed when desired. It will be further 35 noted that the size of the circular portion formed by the twisted wires may be changed somewhat according to the extent the stems 16 are projected through the ears 17.

When this device is in use, the hose-engag-

ing nozzle 1 will be screwed onto the usual 40 coupling at the end of a hose and the nozzle 2 can then be adjusted to permit the desired 45 amount of water to flow through the same from the nozzle 1. The lock-nut 7 can then be tightened to secure the nozzle 2 in the 50 adjusted position or this nut 7 may be left loose in case cleaning is to be performed which requires the flow of water to be 55 changed at different times. This water will spray out through the openings 11 in the end of the nozzle 2 and the brush will be thoroughly saturated. As previously explained, the brush may be removed and a new one easily and quickly put in place and further when so desired, the nozzle 2 may be entirely removed from the nozzle 1 so that the two nozzles may be thoroughly cleaned.

I claim:

A fountain brush comprising a brush 60 head composed of bristles and a looped twisted wire core constituting a retainer for said bristles, the free ends of said core being extended inwardly beyond said head, a fluid supply nozzle having an elongated distributor disposed for discharging fluid into the center of said head, said nozzle being equipped with substantially diametrically opposed apertured ears, the free ends of said core passing through and inwardly beyond 70 said ears, and a clamping band encircling said nozzle and having diametrically opposed outwardly bent portions forming pockets for reception of the extremities of 75 said free ends.

In testimony whereof I have hereunto affixed my signature.

GEORGE A. MEISNER.
